To all whom it may concern:

Be it known that we, WILLIAM SCHNELL and ERIC S. CARLSON, both citizens of the United States, residing respectively at 5571 Clarendon Avenue, Detroit, in the county of Wayne and State of Michigan, and 765 Central Avenue, Detroit, in the county of Wayne and State of Michigan, have invented a new, original, and ornamental Design for an Automobile Radiator Ornament or Similar Article, of which the following is a specification, reference being made to the accompanying drawing forming part thereof.

Fig. 1 is a side elevation of an automobile radiator ornament or similar article, showing our new design;

Fig. 2 is a plan view of the same;

Fig. 3 is a front elevation of the same.

We claim:

The ornamental design for an automobile radiator ornament or similar article substantially as shown.

WILLIAM SCHNELL.
ERIC S. CARLSON.
